(57) **CLAIM**

The ornamental design for an LED display housing, as shown and described.

DESCRIPTION

FIG. 1 is a front perspective view of an LED display housing showing our new design; according to one embodiment of the present invention;

FIG. 2 is a front view thereof;

FIG. 3 is a first side view thereof;

FIG. 4 is an opposing second side view thereof;

FIG. 5 is a rear view thereof;

FIG. 6 is a top view thereof;

FIG. 7 is a bottom view thereof; and,

FIG. 8 is a rear perspective view thereof.

The broken lines in the drawing are for the purpose of illustrating unclaimed portions of the LED display module and form no part of the claimed design.
